UNITED STATES PATENT OFFICE.

EDWIN C. ROSENBERG, OF MILWAUKEE, WISCONSIN.

FOLDING BRUSH.

1,283,920.

Specification of Letters Patent.

Patented Nov. 5, 1918.

Application filed May 14, 1917. Serial No. 168,505.

To all whom it may concern:

Be it known that I, EDWIN C. ROSENBERG, a citizen of the United States, residing at Milwaukee, in the county of Milwaukee and 5 State of Wisconsin, have invented certain new and useful Improvements in Folding Brushes, of which the following is a specification.

This invention relates to new and useful 10 improvements in brushes and the principal object of the invention is to provide means whereby the bristles may be inclosed when the brush is not in use.

Another object of the invention is to make 15 the brush head in the form of a box and to pivot the brushes therein so they may be moved to project from the box or to lie within the same.

A further object of the invention is to 20 secure the bristles in a series of frames and to pivot these frames within the box, and to provide a cover for closing the bristles in the brush head.

Another object of the invention is to 25 provide a device of this character, which is simple and durable in its construction, reliable and efficient in operation and one which can be manufactured and placed upon the market at a minimum cost.

The invention also consists in certain 30 other features of construction and in the combination and arrangement of the several parts, to be hereinafter fully described, illustrated in the accompanying drawings and 35 specifically pointed out in the appended claims.

In describing my invention in detail, reference will be had to the accompanying 40 drawings, wherein like characters denote like or corresponding parts throughout the several views, and in which:

Figure 1 is a side view of the invention.

Fig. 2 is a longitudinal sectional view.

Fig. 3 is a transverse section.

Fig. 4 is a section on line 4—4 of Fig. 2.

Fig. 5 is a sectional detail.

Fig. 6 is a longitudinal section through the bristles and their supporting case.

In these figures 1 indicates the brush head 45 made in the form of an oblong casing and having its bottom and one end open. The top of the casing at the open end is provided with lugs 2 forming a bearing for a pin 3 which acts as a hinge for the end cover 4, 50 for closing the end of the casing. A pin 5 is carried at the lower end of this cover and

this pin acts as a hinge for the cover 6 for the casing. This cover is provided with spring catches 7 engaging with projections 8 on the side plates 9 of the casing to hold 55 the cover closed. These catches are disengaged from the projections by means of the spring tongues 10 provided in the sides of the casing and being similar to the buttons used in folding cameras. The casing and 60 cover are covered with leather 11 or other suitable material and these buttons are concealed by this covering. The side plates 9, before mentioned, are secured to the inner part of each of the long sides of the casing 65 and these plates are provided with convex portions 9' located at intervals along the length of the plate and the said portions on one plate being directly opposite similar portions on the other plate. These portions 70 are provided with openings forming bearings for the bristle carrying members 11' which are provided with rods 12 projecting from the members and fitting in these openings. These members are each formed of 75 sheet metal, doubled upon itself to form a casing and having the upper end thereof enlarged as at 13 through which passes the rod 12. The body part of this casing is 80 curved as shown in Fig. 6. The bristles 14 are looped over the rod 12 and their free 85 ends project from the casing. The sides of the casing are held together to grip the bristles by the clip 15. If desired these casings may be formed with a series of 90 enlargements 16, each enlargement to receive a bunch of bristles and to hold each bunch spaced apart from the adjoining bunches.

The bristle carrying members are connected together by means of a rod 17 which 95 is provided with a plurality of pairs of trunnions, 18, a pair for each member, and each member is provided with a slot 19 in its lower edge and with the recess 20 on each side of the slot to receive the trunnions. 100 Thus it will be seen that the members may have oscillating movement in the casing and the movement of one member will cause all the other members to move therewith by reason of the fact that they are locked together by the bar 17.

I provide means for normally holding the bristles in open position, that is, projecting from the casing, and these means consist of a plate 21 engaging a hook 22 on the adjacent member 11' and this plate is pivoted at 110 23 in the top of the casing, intermediate

its ends, and its other end is engaged by a spring button 24 in the top of the casing, this button being similar to the button 10 in the sides of the casing. The plate tends 5 to force the bristles into open position by means of a spring, not shown, on the pin 24' and engaging the plate. When the bristles are in open position the plate is in locked engagement with the hook 22 so that 10 there is no danger of the bristles closing while the brush is being used, and it is necessary to push the button 24 to throw the plate 21 out of engagement with the hook.

When desired I may form a pocket 25 on 15 the top of the casing for receiving a comb. This pocket is formed by leaving the leather covering at the top of the casing free from the top as shown.

When it is desired to use the brush, the 20 tongues 10 are pressed in to release the cover and the same is carried to the back of the brush as shown in dotted lines in Fig. 2. This will permit the spring pressed plate 21 to force the bristle carrying parts to assume 25 their upright positions with the bristles in operative position and the brush ready to be used.

After the brush has been used and it is desired to close the same, the button 24 is 30 pressed in to cause the plate 21 to release the hook 22 and then the cover is swung into closing position which will cause the bristles to assume a closed up position as shown in Fig. 2.

35 The brush may be made for the use of the hair, clothes or shoes or for any other purpose and can be made of different grades of material.

The brush may be made of any suitable 40 material and of any suitable shape.

It is thought from the foregoing that the advantages and novel features of my invention will be readily apparent.

I desire to be understood that I may make 45 slight changes in the construction and in the combination and arrangement of the several

parts, provided that such changes fall within the scope of the appended claims.

I claim as my invention:

1. A brush comprising a casing, a plurality of bristle carrying members pivotally secured therein, means for connecting said members together, a hook secured to one of said members, a spring pressed plate engaging said hook for normally urging said 55 bristle carrying members in a position to project the bristles thereof, said plate being in locked engagement with said hook when said bristle carrying members are in an opened position, and means for operating said spring plate to unlock the plate from the hook.

2. A brush comprising a casing, a plurality of bristle carrying members pivoted therein and provided with slots having recesses upon each side thereof, a rod connecting said members, said rod provided with a plurality of pairs of trunnions for pivotal engagement with the recesses in said bristle carrying members, and means for swinging 70 said bristle carrying members to project or inclose the bristles.

3. A brush comprising a casing having its bottom pivoted thereto, a plurality of bristle carrying members pivoted in said casing 75 and held in said casing by the bristles thereof engaging with said bottom, means connecting said members together, one of said members being provided with a hook, and a spring pressed plate engaging with said 80 hook for swinging the bristle carrying members to an open position and locking them in such position when the bottom of the casing is open, and means for disengaging the plate and hook.

85 In testimony whereof I affix my signature in presence of two witnesses.

EDWIN C. ROSENBERG.
